(Cl. D49—1)

FIG. 1

FIG. 2

FIG. 4

FIG. 3

Figure 1 is a perspective view of a combined top and rear control panel for a washing machine or similar article embodying my new design;

Figure 2 is a cross-sectional view taken on the line 2—2 of Figure 1;

Figure 3 is a fragmentary side elevational view of the rear portion of the combined top and rear control panel; and

Figure 4 is a top plan view of the fragmentary portion shown in Figure 3.

The essential features of the design reside in those portions shown in full lines.

I claim:

The ornamental design for a combined top and rear

control panel for a washing machine, or similar article, as shown and described.
